(57) **CLAIM**

The ornamental design for an air conditioner as shown and described.

DESCRIPTION

Air conditioner

1.1: Front view of an air conditioner;

1.2: Right side view thereof;

1.3: Back view thereof;

1.4: Left side view thereof;

1.5: Top plan view thereof; and

1.6: Left side perspective view thereof.

The broken lines depict portions of the air conditioner and form no part of the claimed design.
